UNITED STATES PATENT OFFICE

THOMAS J. MILES, OF BUECHEL, KENTUCKY

CHAIR

Application filed September 16, 1929. Serial No. 392,855.

This invention relates to furniture and has special reference to a folding chair of the type commonly called lawn or porch chairs.

With the usual chair of this class a strip of canvas forms the back and seat, being attached at its lower end to a front frame bar and at its upper end to a top frame bar. Also, the frame may be adjusted so that the user may sit up practically straight or lean backward to a suitable position, the adjustment being by engagement of a cross member of one part of the frame in notches in another part of the frame. This kind of a chair can only be adjusted while it is unoccupied so that a person using the chair and desiring to change the angle at which he is sitting is obliged to rise in order to make the change.

One object of the present invention is to provide an improved general construction of chairs of this character wherein provision is made for adjustment of the chair while occupied.

A second important object of the invention is to provide such a construction in the chair that the adjustment may be obtained by the user simply inclining his body to the position in which he wishes to rest, the chair automatically adjusting itself to that position.

Porch chairs, as commonly constructed, are without rollers or castors and are frequently dragged around on the floor to the injury of the floor paint or other finish.

A third important object of the invention is to provide a novel construction of folding chair having rollers on its front legs which ordinarily support the front of the chair but which, upon a person leaning forward, as in rising from the chair, are automatically raised from the ground so that no slipping of the chair will take place while one is rising therefrom.

A fourth important object of the invention is to provide, in such an automatically adjustable chair, a novel arrangement of parts by which the forward inclination of the chair back, as a person rises therefrom is limited so that danger of the chair collapsing forwardly is eliminated.

With the above and other objects in view, as will be hereinafter apparent, the inven-

tion consists in general of certain novel arrangements of parts and combinations of elements hereinafter fully described, illustrated in the accompanying drawings and specifically claimed.

In the accompanying drawings like characters of reference indicate like parts in the several views, and:

Figure 1 is a side elevation of the improved chair in its erect position.

Figure 2 is a similar view showing the back of the chair inclined to one position of reclining adjustment.

Figure 3 is a front elevation of the chair in the position shown in Figure 2.

Figure 4 is a side elevation of the chair as folded.

Figure 5 is a rear elevation of the folded chair.

Figure 6 is a view similar to Figure 1 but showing a modified means for engaging the ground brought into use upon a person rising from the chair.

Figure 7 is a view similar to Figure 2 but showing the modification.

In the construction of the chair as here shown there are provided two frames intersecting each other at nearly right angles when the chair is unfolded. For convenience these frames may be designated as the back frame and the seat frame.

Referring to the chair in its set-up or erected position as shown in Figures 1, 2 and 3, the back frame will be seen to consist of a pair of laterally spaced upwardly and rearwardly extending side bars 10 which are connected adjacent their bottom ends by a back frame cross bar 11. This bar 11 lies behind the bars 10 and its ends project outwardly beyond the bars 10 to form stops 12 the purpose of which will be presently explained. At the upper ends of the bars 10 these bars are connected by an upper back frame cross bar 13.

The seat frame consists of two upwardly and forwardly extending side bars 14 which are connected adjacent their lower or rear ends by a rear seat frame cross bar 15. Beneath the forward ends of the bars 14 are the seat brackets 16 and the under sides of these

brackets are connected by forward seat frame cross bars 17. To the rearmost of the bars 17 is secured the forward end of a loose canvas seat and back strip 18 which extends upward 5 to be connected with the bar 13. It will be noted that the back frame lies within the seat frame but is free to slide therethrough and to assume various angular relations therewith. Spaced from the crossing point 10 of the two frames are pivot bolts 19 and 20 passing respectively through the bars 10 and 14 and arm pieces 21 forming upper tie members between the frames are connected to said frames by these bolts.

15 Adjacent the lower ends of the bars 10 is a pivot rod 22 and on this rod is pivoted the forward ends of lower frame tie bars 23 the rear ends of which are pivoted on pivot bolts 24 spaced forwardly from the rear ends of 20 the bars 14. These bars 23 tie outside of the seat frame and they are therefore spaced from the lower ends of the bars 10 so that rollers 25 may be mounted on the bolts 22 between the bars 23 and 10. Washers or 25 spacers 25' are used to hold the rollers free from the bars 23 and 10. By reference to Figures 2 and 1 it will be seen that the bars 23 have their forward ends 23' projecting some distance in front of the rollers 25 so 30 that, as a person rises from the chair, these ends will engage the ground by the forward tilting movement of the chair and will thus lift the rollers off the ground. This action will prevent the lower part of the chair rolling 35 backwardly to the possible injury of the user.

In the modified form shown in Figures 6 and 7, the bars 10 project downwardly below the rollers 25 to form ground engaging extensions 26 which will dig into the surface 40 of a lawn when the chair is in the position shown in Figure 6 or, if the chair is on a hard surface such as a porch floor will act in such position to raise the rollers off the 45 surface and will thus prevent the chair slipping backwardly as a person rises. It will also be noted from Figures 1 and 6 that the bars 14 engage the stops 12 when the chair is in its most upright position, as when one 50 rises, and thus further forward movement of the back frame and consequent collapse is prevented.

In use one sits in the chair as at Figure 1 and by simply leaning backwardly the back 55 frame is tilted rearwardly, this tilt raising the front of the seat frame and of course lifting the weight of the user so that the tendency of the chair during occupancy is always to assume the position of Figure 1, the 60 resting of the user's feet on the floor being sufficient to resist this tendency to forward movement and to maintain the back at whatever angle the user desires. The chair is folded by simply pulling up on the forward 65 end of the seat frame whereupon the parts

will assume a position such as in Figure 4, the stops 12 engaging the bars 14 to limit this folding movement.

There has thus been provided a simple and efficient device of the kind described and for the purpose specified.

It is obvious that minor changes may be made in the form and construction of the invention without departing from the principles involved so that it is desired to include all forms of the invention which fall within the scope claimed.

Having thus described the invention, what is claimed as new, is:—

1. In a folding chair, a back frame, a seat frame crossing the back frame and slidable and tiltable relative thereto, rigid connecting arm supporting bars pivoted directly to and connecting the sides of the back frame with the sides of the seat frame above the crossing point of said frames, other rigid connecting bars pivoted directly to and connecting the sides of said frames below said crossing point, a flexible seat and back strip suspended between the sides of said frames loosely and having its ends connected to the front of the seat frame and upper part of the back frame respectively, ground engaging rollers on the lower ends of the sides of the back frame, and ground engaging parts mounted upon the lower ends of the back frame and projecting forwardly of said rollers to engage the ground upon the chair being tilted forwardly.

2. In a folding chair, a back frame, a seat frame crossing the back frame and slidable and tiltable relative thereto, rigid connecting arm supporting bars pivoted directly to and connecting the sides of the back frame with the sides of the seat frame above the crossing point of said frames, other rigid connecting bars pivoted directly to and connecting the sides of said frames below said crossing point, a flexible seat and back strip suspended between the sides of said frames loosely and having its ends connected to the front of the seat frame and upper part of the back frame respectively, stops on the back frame positioned to engage the seat frame and limit downward movement of the front thereof, ground engaging rollers on the lower ends of the sides of the back frame, and ground engaging parts mounted upon the lower ends of the back frame members and projecting forwardly of said rollers to engage the ground upon the chair being tilted forwardly.

3. In a folding chair, a back frame, a seat frame crossing the back frame and slidable and tiltable relative thereto, rigid connecting arm supporting bars pivoted directly to and connecting the sides of the back and seat frames above their points of intersection, other rigid connecting bars pivoted to the sides of the back and seat frames below their

points of intersection, the pivotal connections between the last mentioned bars and the sides of the back frame constituting roller axles, ground engaging rollers mounted on said axles, and ground engaging extensions on the forward ends of the last mentioned bars projecting forwardly of the rollers to engage the ground upon the chair being tilted forwardly.

- 10 4. In a folding chair, a back frame, a seat frame crossing the back frame and slidable and tiltable relative thereto, rigid connecting arm supporting bars pivoted directly to and connecting the sides of the back and seat frames above their points of intersection, other rigid connecting bars pivoted to the sides of the back and seat frames below their points of intersection, the pivotal connections between the last mentioned bars and the sides 15 of the back frame constituting roller axles, ground engaging rollers mounted on said axles between respective last mentioned bars and the sides of the back frame, and ground engaging extension on the forward ends of 20 the last mentioned bars projecting forwardly of the rollers to engage the ground upon the chair being tilted forwardly.

In testimony whereof I affix my signature.
THOMAS J. MILES.
